UNITED STATES PATENT OFFICE

2,324,091

ROCKING CHAIR

Walter La Valliere, Sheboygan, Wis.

Application June 12, 1941, Serial No. 397,783

1 Claim. (Cl. 155—50)

This invention relates to the official class of seats and chairs and more particularly rocking chairs.

The primary object of this invention resides in the provision of a rocking chair adapted to yield in all directions relative to its support.

Another object of this invention resides in the particular construction of the support of the chair.

A further object of this invention resides in the particular construction of the base of the chair.

A still further object of this invention resides in the particular manner of mounting the base of the chair on the support.

Aside from the aforesaid objects this invention resides in the particular manner of assembling the springs on the base of the chair.

Among the salient features of this invention is the particular construction of the spring units.

With these and other objects in view this invention resides in certain novel features of construction and arrangement of elements to be hereinafter more particularly set forth in the specification, illustrated in the accompanying drawings and pointed out in the appended claim and, while this disclosure depicts my present conception of the invention, the right is reserved to resort to such changes in construction and arrangement of elements as come within the spirit of the invention.

In the accompanying drawings forming a part of this application;

Fig. 1 is a side view of the chair support and base mounted thereon showing the super structure thereof in dotted lines.

Fig. 2 is a plan view thereof.

Fig. 3 is a perspective view of the chair base.

Fig. 4 is a similar view of the chair support.

In the present illustration of this invention the number 5 designates, in general, a rocking chair consisting of a support 6, a seat supporting base 7 and super structure 8 herein indicated by dotted lines as the same may be of any well known construction and upholstered in any style desired.

The support 6 preferably consists of legs 9 connected by front and rear cross bars 10 upon which is secured, as by bolts 11, spaced pillars 12.

The base 7 consists of long rear and short front beams 13 and 13' connected together by spaced straps of rigid metal 14 provided with a series of apertures 15 and disposed between each pair of straps is an intermediate strap 16 also provided with apertures 17, said intermediate straps are suspended from or connected to the first

mentioned straps by a series of cross springs 18 and are provided with apertures 19 adapted to receive the free ends of the bolts 11 for swingably and yieldably securing the base on the pillar 5 of the support, the securing element being in the form of nuts 20 or other suitable fastening means.

With the base of the chair secured on the support thereof as heretofore set forth, the weight of an individual occupying the chair will be yieldingly supported by the springs and, through the particular connection of the base to the pillars, the chair is permitted to not only yield in a perpendicular plane but will swing in all directions, thus promoting a high degree of comfort to the occupant thereof.

Through the instrumentality of the assemblage of elements herein set forth it is manifest that a rocking chair is provided which is simple in construction and cheap to manufacture without departing from optional styling.

Having thus described my invention what I claim and desire to protect by Letters Patent is:

A rocking chair comprising a support including 25 legs, front and rear cross bars connecting the legs adjacent their forward and rearward ends, spaced pillars having their opposite ends resting on and secured to the aforesaid front and rear cross bars inwardly of the legs, said pillars 30 having the medial portions of their upper areas cut out, bolts passing through the cross bars and end portions of the pillars with upper ends extending beyond the upper surfaces of the end portions of the pillars, short stationary straps 35 having apertures therein receiving the upper ends of the bolts and having other apertures disposed at intervals throughout their lengths, a seat supporting base including front and rear cross beams connected by straps of greater length than the aforesaid short straps disposed on opposite sides 40 of the short straps in parallelism thereto and having apertures therein disposed in spaced relation with the apertures in the short stationary straps, said beams being disposed forwardly and rearwardly of the ends of the short stationary straps, 45 fastening elements threadedly disposed on the upper ends of the bolts and securing the short stationary straps on the pillars, and laterally extending coil springs disposed between each short stationary strap and adjacent straps of the aforesaid seat base on opposite sides thereof with 50 their opposite ends secured in the apertures of the short stationary straps and straps of the seat base.
